UNITED STATES PATENT OFFICE.

LEWIS H. BULLARD, OF KALAMAZOO, MICHIGAN.

PUNCHING-MACHINE.

1,305,766.

Specification of Letters Patent. Patented June 3, 1919.

Application filed December 16, 1918. Serial No. 266,913.

To all whom it may concern:

Be it known that I, LEWIS H. BULLARD, a citizen of the United States, residing at the city and county of Kalamazoo, State of Michigan, have invented certain new and useful Improvements in Punching-Machines, of which the following is a specification.

This invention relates to improvements in punching machines.

10 The main objects of this invention are to provide an improved punching machine provided with a stripper in which the stripper is automatically returned after performing its function, leaving the punch exposed and thus facilitating its adjustment to the work.

Further objects, and objects relating to structural details, will definitely appear from the detailed description to follow.

I accomplish the objects of my invention 20 by the devices and means described in the following specification. The invention is clearly defined and pointed out in the claims.

A structure which is a preferred embodiment of my invention is clearly illustrated in 25 the accompanying drawing, forming a part of this specification, in which:

Figure I is a side elevation of a punching machine embodying the features of my invention.

30 Fig. II is a detail vertical section on a line corresponding to line 2—2 of Fig. I, the punch and its actuating means and certain other parts being shown in full lines for convenience in illustration.

35 Fig. III is a detail section similar to that of Fig. II with the parts in actuated position.

40 Fig. IV is a detail view partially in section of parts shown in Figs. II and III, showing the punch on its return movement just prior to releasing the stripper.

45 Fig. V is a detail side elevation with the plunger and stripper in actuated or extended position, one of the housing members and the stripper return springs being omitted.

Fig. VI is a detail horizontal section on a line corresponding to line 6—6 of Figs. I and II.

50 Fig. VII is a detail horizontal section on a line corresponding to line 7—7 of Figs. I and II.

55 Fig. VIII is a plan view of the blank from which one of the housing members is made.

In the drawing similar reference charac-

ters refer to similar parts throughout the several views, and the sectional views are taken looking in the direction of the little arrows at the ends of the section lines. 60

Referring to the drawing, the body 1 is slotted at 2 to receive the work, the die 3 being carried by the lower arm of the body, while the punch 4 is carried by the upper arm. The punch is arranged to reciprocate 65 in the head 5 which is threaded at its upper end to receive the actuating member 6 provided with a removable handle 7. The punch is provided with a disk-like head 8 engaged in the laterally opening slot-like 70 recess 9 in the lower end of the actuating member providing a swivel connection for the actuating member and punch.

The head is faced off on opposite sides, as at 10, to receive the arms 11 of the U-shaped 75 stripper 12. The arms of the stripper have longitudinal slots 13 therein and notches 14, the notches 14 opening at the upper ends of the arms.

The housing members 15 are preferably 80 sheet metal stampings secured to the head to embrace the arms of the stripper and provided with lugs 16 projecting into the slots of the arms. In these slots I arrange the coiled springs 17 with their lower ends 85 resting upon the lugs and their upper ends engaging the upper ends of the slots, so that they tend to hold the stripper in its retracted position.

The punch is provided with a shoulder 18 90 which, on the forward movement of the punch, engages the stripper and carries it to work engaging position, as shown in Figs. III, IV and V, in which position it is retained by the dogs 19 which reciprocate 95 through holes 20 in the sides of the heads, the dogs being carried inwardly to engaging position by the coiled springs 21, the dogs and springs being housed by the housing members 15. On the return movement 100 of the plunger these dogs are engaged by the beveled annular shoulder 22 on the punch which carries or forces them outwardly, thereby releasing the stripper and allowing it to be retracted by its springs, so that the 105 end of the punch is left exposed as shown in Figs. I and II, facilitating the positioning of the punch on the work.

In punches of this general type now in quite general use it is necessary to fully 110 retract the punch to strip the work and again advance the punch to project its end

to facilitate the pointing or positioning on the work.

By my improved means the operation of the machine is greatly facilitated, a lesser degree of movement of the punch is required, and the step of advancing it to enable convenient positioning on the work is obviated. The die carrying arm of the body is provided with a seat having conical shoulders 10 23, while the die 3 is provided with a corresponding or coacting conical shoulder and is held in place by the threaded support 24. This avoids the necessity of threading the die and at the same time the die is properly 15 centered and supported. The advantages of obviating the threading of the die will be appreciated by those skilled in the art.

I have illustrated and described my improvements as I have embodied the same in 20 a hand machine having the threaded actuating member for the punch. My improvements are, however, adapted and desirable for use in other types or forms of machines. I have not illustrated or described such 25 modifications or adaptations or certain variations in structural details which I contemplate as I believe the disclosure made will enable those skilled in the art to which my invention relates to embody or adapt the 30 same as may be desired.

Having thus described my invention, what I claim as new and desire to secure by Letters Patent, is:

1. In a punching machine, the combination 35 of a body provided with a head, a punch actuating member threaded into said head, a punch reciprocating in said head and having swivel engagement with said actuating member, a U-shaped stripper embracing said head, said stripper being advanced to work 40 engaging position by the actuation of the punch and having longitudinal slots in its arms, a pair of T-shaped stripper dogs reciprocating in said head transversely of said 45 punch and stripper arms to coact therewith, said punch being provided with an outwardly racing annular beveled shoulder positioned to release the dogs on the return movement of the punch, permitting the re- 50 traction of the stripper to expose the end of the punch, actuating springs for said dogs, housing members for said stripper arms and dogs having lugs projecting into said slots, and stripper return springs arranged in said 55 stripper arm slots and supported by said lugs.

2. In a punching machine, the combination 60 of a body provided with a head, a punch reciprocating in said head, a U-shaped stripper embracing said head, said stripper being advanced to work engaging position by the actuation of the punch and having longitudinal slots in its arms, a pair of T-shaped stripper dogs reciprocating in 65 said head transversely of said punch and

stripper arms to coact therewith, said punch being provided with an outwardly facing annular beveled shoulder positioned to release the dogs on the return movement of the punch, permitting the retraction of the 70 stripper to expose the end of the punch, actuating springs for said dogs, housing members for said stripper arms and dogs having lugs projecting into said slots, and stripper return springs arranged in said stripper arm 75 slots and supported by said lugs.

3. In a punching machine, the combination of a body provided with a head, a punch actuating member threaded into said head, a punch reciprocating in said head 80 and having swivel engagement with said actuating member, a U-shaped stripper embracing said head, said stripper being advanced to work engaging position by the actuation of the punch, a pair of stripper 85 dogs reciprocating in said head transversely of said punch and stripper arms to coact therewith, said punch being provided with trip means positioned to release the dogs on the return movement of the punch, permitting the retraction of the stripper to expose the end of the punch, actuating springs for 90 said dogs, and a return spring for said stripper.

4. In a punching machine, the combination of a body provided with a head, a punch reciprocating in said head, a U-shaped stripper embracing said head, said stripper being advanced to work engaging position by the actuation of the punch, a pair of stripper 100 dogs reciprocating in said head transversely of said punch and stripper arms to coact therewith, said punch being provided with trip means positioned to release the dogs on the return movement of the punch, permitting the retraction of the stripper to expose the end of the punch, actuating springs for said dogs, and a return spring for said stripper.

5. In a punching machine, the combination with a body, of a reciprocating punch, a coacting reciprocating stripper, a stripper dog reciprocating transversely of said punch and stripper, said punch being adapted to release said dog on the return movement of the punch, the punch being advanced to its work engaging position by the actuation of the punch, and a return spring for said stripper.

6. In a punching machine, the combination with a body, of a reciprocating punch, a coacting reciprocating stripper, and a stripper dog reciprocating transversely of said punch and stripper, said punch being adapted to release said dog on the return 115 movement of the punch, the punch being advanced to its work engaging position by the actuation of the punch.

7. In a punching machine, the combination of a body, a reciprocating punch, a co- 120

- acting reciprocating stripper adapted to be advanced to work engaging position by the actuation of the punch, a holding dog for said stripper, said punch constituting a releasing means for said dog on the return movement of the punch permitting the retraction of the stripper to expose the end of the punch, and a return spring for said stripper.
- 10 8. In a punching machine, the combination of a body, a reciprocating punch, a co-acting reciprocating stripper adapted to be advanced to work engaging position by the actuation of the punch, and a holding dog for said stripper, said punch constituting a releasing means for said dog on the return movement of the punch permitting the re-

traction of the stripper to expose the end of the punch.

9. In a punching machine, the combination with a body, of a reciprocating punch, a coacting reciprocating stripper, means for holding said stripper in work engaging position adapted to be released by the return movement of the punch, permitting the retraction of the stripper, and a return spring for said stripper.

In witness whereof I have hereunto set my hand and seal in the presence of two witnesses.

LEWIS H. BULLARD. [L. S.]
